UNITED STATES PATENT OFFICE.

WILLIAM LOCHHEAD, OF HALIFAX, ENGLAND, ASSIGNOR TO FIRTH, WILLIAMS & CO.

DESIGN FOR CARPETS.

Specification forming part of Design No. 5,240, dated August 29, 1871.

To all whom it may concern:

Be it known that I, WILLIAM LOCHHEAD, of Halifax, in the county of York, in that part of the United Kingdom of Great Britain and Ireland called England, designer, have invented a new and original Design for Carpets, of which the following is a specification:

The nature of my design is fully represented in the accompanying photographic illustration, to which reference is made, and is marked or numbered with the figures 728.

I claim as my invention—

The design for a carpet, as shown.

WILLIAM LOCHHEAD.
